UNITED STATES PATENT OFFICE

WILLIAM E. COOK, OF ST. GEORGE, NEW YORK, ASSIGNOR TO GENERAL CABLE CORPORATION, OF NEW YORK, N. Y., A CORPORATION OF NEW JERSEY

WIRE SPLICER

Application filed August 9, 1928. Serial No. 298,500.

My invention relates to wire splicers, and more particularly to a splicer for use in stringing either solid or stranded conductor wires of the larger sizes.

5 At the present time, the general practice is to use hard copper conductor wires, solid or stranded, having high tensile strength, since even with fairly short runs of conductor wire, its sagging and swaying, coupled with 10 its weight, may result in objectionable elongation, if soft wire be used. Heavy wires, solid or stranded, in connection with which the splicer of my invention is adapted to be used, are delivered in fairly short lengths 15 upon reels, the footage upon these reels varying with the diameter of the wire.

Consequently, it is necessary for the linemen to splice different lengths of wire when running a line, and heretofore and up to the 20 present time, the practice has been to connect the ends of different lengths of wire by brazing them together, both as to solid and stranded wire, which practice not only consumes considerable time, but weakens the wire at 25 the joint.

With small gauge wires, which can be twisted and soldered, there is no difficulty in making a strong splice having good conductive properties. With heavy wires, either 30 solid or stranded, however, twisting cannot be resorted to, and notwithstanding that wires of high tensile strength may be used, the strength of the strung wires at the splices, when brazing methods are used, affords points 35 in the line, the tensile strength of which are very much less than that of the wire itself, and unless great care is exercised when making each joint, there may be a lower rate 40 of conductivity of the line at a joint.

45 With the above conditions in mind, I have produced a splicer by which the ends of different lengths of wire in a conductor line, may be mechanically and electrically connected in a manner which will not only permit a rapid 50 formation of the joint, but which will make the strength of the line, at the splice or joint, greater than the tensile strength of the wire 55 itself.

55 In a splicer embodying the invention, there 60 is no possibility of a weakening of the joint,

due to the strains thereon from the sagging or swaying of a wire, since the action of such sagging or swaying will have the effect of increasing the effectiveness of the joint secured by means of the splicer. Furthermore, 55 the construction of the splicer is such as to avoid any possible lowering of the conductivity of the line at the joint, means preferably being provided which will ensure an effective electrical connection between the ends 60 of the two lengths of wire as well as through the body of the splicer. In fact, in a splicer embodying my invention, the conductivity of the splicer is very much greater than that of the wire in connection with which it is used, and ample contacting surfaces between the splicer and the wire are afforded, so as to avoid any possible lowering of the conductivity of the line, irrespective of the number 65 of splices there may be therein. 70

I also so construct the splicer as to ensure its engagement with an effective length adjacent the end of the wire of each length, and avoid any necessity for the exercise of any particular care by the lineman when making 75 the splice.

In a device of the character to which my invention relates, production cost is no factor since its utility grows out of the saving 80 of time in making the joint, and the increase in the safety factor due to the absence of all possibility of weak spots along the line arising from improper brazing operations, and the effect of heat upon the wire when making such joints by brazing. 85

The effectiveness of the joints secured by a splicer of my invention results from its construction and is not dependent in any way upon the linemen, since no tools are required in making a joint. Furthermore, when 90 a splicer has once been used to connect two adjoining sections of wire, it becomes practically an integral part of the line, since separation of the two ends is practically impossible. 95

The invention consists primarily in a wire splicer embodying therein a sleeve of electro-conductive material, open at both ends, a plurality of substantially abutting gripper jaws 100 of electro-conductive material within, ad-

- jacent and substantially co-terminus with each end and movable axially of said sleeve, said sleeve and said jaws having elongated coacting wedging surfaces, and resilient means acting to thrust said jaws outwardly of said sleeve, whereby said jaws will be opened upon the insertion of a wire therein, and will be automatically closed by said resilient means following such insertion of the wire, and outward movement of the wire or axial strains thereon will increase the gripping action of said jaws; and in such other novel features of construction and combination of parts, as are hereinafter set forth and described, and more particularly pointed out in the claims hereto appended.
- 10 Referring to the drawings, Fig. 1 is a side elevation of a wire splicer embodying my invention and the ends of two lengths of wire connected thereby;
- 15 Fig. 2 is a longitudinal section thereof upon a larger scale;
- 20 Fig. 3 is a transverse section on the line 3—3 of Fig. 2; and
- 25 Fig. 4 is an enlarged detail view of the spacer for controlling the extent of penetration of the ends of the wire lengths to be spliced, while ensuring an electrical contact between the ends of the wire and the splicer.
- 30 Like letters refer to like parts throughout the several views.

In the embodiment of the invention shown in the drawings, the main body of the splicer is composed of a sleeve formed of two sections *a* and *a'*, this sleeve being open at each end. The bore of the sleeve adjacent each open end thereof is interiorly tapered so as to form wedge surfaces within the sleeve. The exterior tapering of the sleeve, at the ends thereof, is merely for avoiding excess metal in the sleeve and for facilitating the binding of insulating tape about the splicer when the same is used in connection with insulated wire.

45 The sleeve is made up of two sections *a* and *a'* to permit the assembling of the device, the two sections preferably being permanently united by brazing, sweating, or soldering after assembly, to avoid possible tampering with the active mechanisms of the splicer and ensure its use without the employment of tools by the linemen.

50 Adjacent each open end of the sleeve *a—a'* is a plurality of gripper jaws *b*, *b'*, *b2* and *b3* or *c*, *c'*, *c2* and *c3*, the outer face of each jaw being tapered at the same angle as the inner face of the sleeve so as to provide, in each set of jaws, wedge surfaces co-operating with the adjacent wedge surface of the sleeve.

60 These jaws may be formed of a truncated metallic cone cut axially to produce the desired number of jaws, a central bore having suitable gripping areas being formed in said cone before separating it into the independent jaws. The gripping area of each jaw prefer-

ably consists of a multiplicity of closely adjacent small teeth *d*, preferably pitched away from the open end of the sleeve. Other forms of gripping areas, however, may be used if desired, provided that the number and strength is such as to prevent possibility of the stripping of the jaws or the wire when stresses are applied thereto.

65 Acting to thrust the jaws adjacent each end of said sleeve, outwardly thereof, so as to have a normal tendency to close said jaws to their maximum extent, is resilient means which, in the form of the invention illustrated, consists of two springs *e* and *f*, one end of each spring being seated against a partition or spacer *g* within the sleeve, and the other end of each spring acting against all of the jaws at one end of the sleeve. By this construction, the jaws at either end of the sleeve may have inward movement against the tension of the spring, and when the pressure upon said jaws is released, the spring will develop sufficient wedging action to set the jaws upon the wire in a manner to be more fully referred to hereinafter.

70 While the partition *g* will, of itself, limit the extent of penetration of a wire end and avoid any possibility of the end of one section of wire interfering with the proper extent of penetration of the other end of the wire to be coupled thereto by means of the splicer, I prefer to use in conjunction with said partition, yieldable contact members engageable by the ends of the wire so as to ensure electrical contact between such ends of the wires and some portion of the splicer.

75 In the accompanying drawings, the partition *g* is shown as being provided with tubular extensions *h* and *i*, in the opposite ends of which are mounted metallic plungers *j* and *k* having contact heads at their outer ends as shown at *j'* and *k'* to prevent either being thrust to more than a limited extent within the tube. Seated between the plungers *j* and *k* is a coiled spring *m* having a normal tendency to thrust said plungers in opposite directions to a limited extent only.

80 The tubular portions *h* and *i* form suitable guides for the springs *e* and *f*.

85 The sections *a* and *a'* of the sleeve of the splicer may be connected in any desired manner, preferably by means of a screw threaded joint, to facilitate the tensioning of the springs *e* and *f* when assembling, but after the parts have been once united, they may be permanently secured in relation to each other by means of soldering, sweating or brazing.

90 The range of movement of the jaws in receiving the ends of adjacent sections of wire is sufficiently great to permit the same splicer to be used with wires of different sizes, although splicers of different dimensions must be used with wires or cables having substantial variation in their diameters,

and the variation of the diameters of wires in connection with which the splicer is designed to be used, will range from one-quarter of a inch to an inch and a half.

5 It is obvious, therefore, that the same splicer might be used where the variation of diameter does not exceed about a quarter of an inch, but that beyond this range, larger or smaller splicers must be used.

10 The extension of the jaws beyond the ends of the sleeve, as shown in the drawings, is largely a matter of convenience, although if desired, such extending ends may have a tool applied thereto for opening the jaws 15 in the event that it is desired to remove a wire therefrom.

The end of one length of wire is shown at *n* and the end of another length of wire to be connected therewith is shown at *o*.

20 Preferably, the sleeve *a*—*a'*, the gripping jaws therein and the spacer are made of a high grade, hard bronze such as Tobin bronze, which may be readily machined and yet possesses inherently greater strength than 25 the wires with which the splicer is to be used.

The operation of the herein described splicer is substantially as follows:—

When the splicer is not in use, the springs 30 *e* and *f* force the oppositely movable sets of jaws *b*, *b'*, *b2* and *b3* and *c*, *c'*, *c2* and *c3* outwardly of the opposite ends of the sleeve *a*—*a'* and hold them firmly in the closed position, reducing the opening within the gripping areas of the jaw sections to its 35 smallest diameter, and one smaller than that of the smallest diameter of wire with which the splicer can be used.

40 Preparatory to, or during the stringing of, adjacent lengths of wire, the lineman merely forces the end of one length of wire *n* against the exposed ends of one set of jaws *b* to *b3* with one hand, while holding the sleeve *a*—*a'* with the other hand. The thrust of the wire overcomes the tension of the spring 45 *e* and moves the jaws inwardly of said sleeve. Since the sleeve is ordinarily held substantially horizontally, the co-operating wedge surfaces exteriorly of the jaws, and interiorly of the sleeve, will permit one or more of 50 the jaws to move away from the others until the opening within the jaws becomes sufficiently enlarged to receive the wire.

Ordinarily, all of the jaws will have substantially the same movement inwardly of 55 the sleeve, but this is immaterial so long as some of the jaws have sufficient movement to secure the necessary enlargement of said opening.

When sufficient clearance between the jaws 60 has been thus secured, the wire will pass freely into this opening, and the spring *e* will immediately set the gripping areas or teeth *d* of the jaws upon the wire, due to the wedging action developed by the thrust of the 65 spring. Irrespective of the extent of pene-

tration of the wire, the strength of the spring and the wedging action will grip the wire sufficiently tightly to prevent movement thereof outwardly of the sleeve, without imparting similar movement to the jaws. 70

Hence, any pull upon the wire, after it has once been inserted within the opening of the jaws, will merely increase the strength of the gripping action. The spring *e* acts merely to develop an initial gripping of the wire by 75 the jaws, and thereafter, longitudinal stresses upon the wire, whether these be merely an attempt to withdraw the wire from the splicer, or the result of sagging, stretching or swaying of the wire after it has been strung, 80 will serve merely to strengthen the gripping action of the jaws. The limitation of the closing action of the jaws will prevent such strains from causing the teeth or other gripping areas *d* to penetrate the wire to an extent to weaken the portion of the wire engaged by said jaws. 85

While pull upon the wire will merely act to increase the gripping action of the jaws, nevertheless the wire may be thrust inwardly 90 of the sleeve to any extent, since the jaws will move freely with the wire against the tension of the spring *e* and could be passed through the sleeve sufficiently, if proper care were not exercised, to engage it with the other jaws *c* to *c3* and interfere with their action, were it not for the use of the spacer *g* limiting such movement. 95

Since a partial withdrawal of the wire from the splicer is neither possible nor desirable, 100 the spacer *g*, or its equivalent, is highly desirable in securing a proper and rapid application of the splicer to the wire, since a lineman will ordinarily force the wire inwardly of the sleeve to the fullest possible extent with a 105 single thrust theretupon, and engage it with the spacer *g* upon the completion of this action. This is also desirable as it will secure electrical contact between the end of the wire and the spacer. 110

The yieldably supported plunger *j* is used to maintain the electrical contact between the wire and the spacer, and with the length of wire *o*. This contact plunger will yield as it 115 is engaged by the wire.

After the end of one length of wire *n* has been properly secured within one set of jaws *b* to *b3*, as above described, the end of the adjacent length of wire *o* is similarly secured within the other set of jaws *c* to *c3*, the procedure and action of the jaws being the same. 120

The spring *m* is normally untensioned, so that the engagement of the end of one wire length *n* with the plunger *j* will merely move the spring and both plungers *j*—*k* axially of the tubes *h* and *i*. The engagement of the end of the other wire length *o* with the plunger *k* will, however, tension said spring and cause that movement of both plungers necessary to 125 establish and maintain electrical contact of 130

the plunger with the wires *n-o* respectively, and form a conductive path through the spring from one to the other.

Since the splicer may be used with wires having a narrow range of difference in diameter, the yieldable contact members *j-k* will fully compensate for varying outward movements of the jaws and wires with wires of different sizes. This, while desirable, is 10 not essential.

In a splicer embodying the invention, the gripping action is so strong that sufficient stress may be applied to heavy wires to break them without disturbing the portions of wire 15 engaged by the jaws.

The multiplicity of teeth *d* not only extends the gripping area along a considerable length of the wire, but permits the use of short teeth which become imbedded in the 20 wire and afford an area of conductivity much greater than the cross section of the wire itself. The co-operating wedge surfaces are, when a wire is positioned in the splicer, forced into such close contact as to avoid any 25 air space, thus ensuring high conductivity through the sleeve itself from one wire length to another.

The portion of a line at the splice is of 30 greater tensile strength, and affords higher conductivity, than the wire itself.

After the application of the splicer to adjacent wire lengths, it may be wound with insulating tape in the manner now followed with a brazed splice.

35 To form a joint with a splicer embodying the invention requires only a few seconds, is done without the use of tools of any kind, and requires no especial care or attention to ensure a perfect electrical connection between 40 two lengths of wire.

While in the drawings, a solid wire is shown, the action of the splicer is the same with stranded wire, and the results are the same, since the wedging action upon the jaws 45 will compact the strands of such wire in a manner to hold all strands firmly in relation to the splicer and to each other. Tests have shown that tensional stresses upon stranded wire will result in the breakage of even the 50 center strand of the wire without any yielding between the wire and the splicer.

It is not my intention to limit the invention to the precise details of construction and combination of parts shown in the drawings, 55 it being apparent that such may be varied without departing from the spirit and scope of the invention.

Having described the invention, what I 60 claim as new and desire to have protected by Letters Patent, is:-

1. A wire splicer embodying therein a sleeve of electro-conductive material, open at both ends, a plurality of substantially abutting gripper jaws of electro-conductive material within, adjacent and substantially co-ter-

minus with each end and movable axially of, said sleeve, said sleeve and said jaws having elongated coacting wedging surfaces, a partition intermediate the ends of said sleeve having tubular extensions thereon, plungers 70 slidably mounted in said tubular extensions respectively, resilient means acting upon said plungers, whereby said plungers will limit the extent of movement of a wire end inwardly of said sleeve, and will have movement 75 with said gripper jaws and said wire end outwardly of said sleeve, and maintain electrical contact with said wire ends, and resilient means acting to thrust said jaws outwardly of said sleeve, whereby said jaws will 80 be opened upon the insertion of a wire therein, and will be automatically closed by said resilient means following such insertion of the wire, and outward movement of the wire or axial strains thereon will increase the 85 gripping action of said jaws.

2. A wire splicer embodying therein a sleeve of electro-conductive material, open at both ends, a plurality of substantially abutting gripper jaws of electro-conductive material within, adjacent and substantially co-terminus with each end and movable axially of, said sleeve, said sleeve and said jaws having elongated coacting wedging surfaces, a partition intermediate the ends of said sleeve 90 having tubular extensions thereon, plungers slidably mounted in said tubular extensions respectively, a spring seated between and acting upon said plungers, whereby said 95 plungers will limit the extent of movement of a wire end inwardly of said sleeve, and will have movement with said gripper jaws and said wire end outwardly of said sleeve, and maintain electrical contact with said wire ends, and resilient means acting to thrust said 100 jaws outwardly of said sleeve, whereby said jaws will be opened upon the insertion of a wire therein, and will be automatically closed by said resilient means following such insertion of the wire, and outward movement of the 105 wire or axial strains thereon will increase the gripping action of said jaws.

3. A wire splicer embodying therein a sleeve of electro-conductive material, open at both ends, and having an interior taper adjacent each open end, a plurality of substantially abutting gripper jaws of electro-conductive material within, adjacent substantially co-terminus with each end and movable axially of, said sleeve, each of said jaws having 115 an exterior taper engaging the interior taper of said sleeve, and having a multiplicity of short teeth presented toward an opening formed within said jaws, a partition intermediate the ends of said sleeve having tubular 120 extensions thereon, plungers slidably mounted in said tubular extensions respectively, a spring seated between and acting upon said plungers, whereby said plungers will 125 limit the extent of movement of a wire 130

end inwardly of said sleeve, and will have movement with said gripper jaws and said wire end outwardly of said sleeve, and maintain electrical contact with said wire ends, and springs acting between said partition and the gripper jaws adjacent each end of said sleeve respectively to thrust said jaws outwardly of said sleeve, whereby said jaws will be opened upon the insertion of a wire there-
in, and will be automatically closed by said springs following such insertion of the wire, and outward movement of the wire or axial strains thereon will increase the gripping action of said jaws.

16 In witness whereof I have hereunto affixed my signature this 7th day of August, 1928.
WILLIAM E. COOK.
